FASHIONING ATTACHMENT FOR KNITTING MACHINES

Morris Philip, New York, N. Y.

Application April 6, 1933, Serial No. 664,689

2 Claims. (Cl. 66—24)

This invention relates to improvements in knitting machines and it is the principal object of my invention to provide a transfer attachment for such machines according to which material thread is transferred from one bed to the other in order to transfer during the operation of the knitting machine automatically certain designs on the goods which heretofore had to be formed in separate machines or by hand.

10. My attachment can be used with any type of machines principally also with jacquard machines to fashion in any design by means of the needles pushed out of the horizontal needle bed according to the jacquard pattern co-operating 15 with the transfer jack needles and the vertical cylinder needles.

Another object of my invention is the provision of a knitting machine attachment equipped with a cam development with which the transfer jacks 20 co-operate to transfer the thread from the horizontal cam-controlled needles to the vertical needles for fashioning a desired design on the knitted goods.

It will be evident that my attachment can be 25 used in the above outlined manner with any type of needle bed arrangement in any type of knitting machines which has more than one needle bed, and that the angle at which the needle beds are arranged in the various type of knitting machines 30 may vary depending on the style of machine with which the attachment is to be used.

Still another object of my invention is the provision of a transfer attachment for knitting machines equipped with means for holding the throats of the horizontal needles open until they 35 are closed during their dropping into a recess of the cam to allow a transfer of the thread to the vertical needles.

A further object of my invention is the provision of a thread loop holder or opening device 40 allowing the opening of any number of threads in any section of the needle bed according to a pre-determined selection for transfer to the cylinder needles.

45. A still further object of my invention is the provision of an attachment for knitting machines by means of which I can make a Jersey sweater with a ribbed bottom part in one piece or any other type of fashioned design on the same.

50. Further objects of my invention are the provision of a lock for the transfer needles operated by the pattern chain, and the provision of a transfer attachment for knitting machines of comparatively simple and inexpensive construction, yet durable and highly efficient in operation and al-

lowing a mounting on any of the knitting machines in use at present without the necessity of material and expensive changes.

These and other objects of my invention will become more fully known as the description thereof proceeds and will then be specifically defined in the appended claims. While I have described my attachment as used with machines having stationary beds and revolving heads in which the cams move, it will be clear that the same may 10 also be used with machines having stationary heads and revolving beds in which the cams are stationary, the only difference being that the parts will operate in reverse manner.

In the accompanying drawings, forming a material part of this disclosure:

Fig. 1 is a fragmentary sectional top plan view of a dial needle bed of the transfer attachment constructed according to my invention.

Fig. 2 shows the transfer jack bed and cams.

Fig. 3 is a perspective detail view of a jack needle.

Fig. 4 illustrates a loop holder in its position before the transfer of the thread.

Fig. 5 is a section on line 5—5 of Figure 1 illustrating the starting position of the jack needle while approaching the dial needle.

Fig. 6 is a view similar to Figure 5 illustrating a portion of the jack needle in position above the dial needle.

Fig. 7 is a section on line 7—7 of Figure 1 illustrating position of the jack needle with its loop falling on a dial needle.

Fig. 8 is a section on line 8—8 of Figure 1 illustrating the dial needle during its backward movement pulling the jack needle with it.

Fig. 9 is a section on line 9—9 of Figure 1 illustrating the positioning of the thread of the cylinder needle on the transfer jack.

Fig. 10 is a section on line 10—10 of Figure 1 illustrating the jack needle moved forward in order to be disengaged from dial needle carrying the thread along.

Fig. 11 is a sectional view, similar to Figure 10 illustrating the position of the jack needle during the lifting of the thread out of the dial needle.

Fig. 12 is a section on line 12—12 of Figure 1 illustrating how the jack needle pulls loop back with the thread and vertical dial needle starting to raise in order to approach loop holder.

Fig. 13 is a fragmentary sectional view of the horizontal and vertical needle beds illustrating the various positions of the parts during the operation of the transfer needles.

As illustrated on top of the flat, horizontal

stationary needle bed 10 rotates the top or cam plate 22 in the direction of arrow. The vertical cylinder needle bed is designated 11 and the attachment carrying the fashioning jack needles 13, is designated 12, and carries the cam members 14, 15 and 16. The cam arrangement for the knitting needles is designated 17 and operated in the usual manner the knitting needles 18 by their bosses 19. The stationary bed for the jack needles is designated 20, while a top plate for the same is designated 21 carrying all cams and moving in the same direction as plate 22 above bed 10.

The loop holder is designated 26 and has an angularly bent outer end 27, and a somewhat upwardly directed pointed inner end 28 for the transfer of the thread from the knitting needles to the vertical cylinder needles 29. The loop holder 26, as illustrated in Figures 4 and 13 is mounted to the casting which carries the cams for the cylinder needles and rotates with that casting, while cam 30 is mounted to the casting that carries the cams for the dial needles and rotates with that casting.

While Figure 4 simply shows the relative position of the loop holder and the vertical cylinder needle and illustrates the stitch in dotted lines after the first end fell off the point 28, the actual structure is clearly shown in Figure 13 where the loop holder 26 on the extreme right shows the position in which the transfer jack 24 took off the stitch from the dial needle and is holding it. The loop holder 26 shown at the left in Figure 13 is shown at the moment when the transfer jack 24 is bent over from the dial needle to match the cylinder needle at which time loop holder 26 has dropped one half of the stitch when the cylinder needle is beginning to enter the stitch C; the needle following is shown as it enters the stitch and loop holder 26 and transfer jack 24 drops the stitch completely.

Cam 30 is one of the main parts of the machine and sets transfer jack 13 into any position by pressing against the wing 25 of the transfer jack 13 so as to adjust it so as to perfectly meet the cylinder needle. The loop holder, as illustrated in Figures 4 and 13 holds the loop which has been taken off by the transfer jack from the dial needle until the cylinder needle enters the loop as for instance shown on the right hand side of Figure 13 where the jack needle is shown aligned with the dial needle. Then the loop holder passes on and the loop drops onto the needle 13 as shown to the left in Figure 13.

In order to swing the jack needles into proper position to the knitting needles for the transfer of the thread a cam 30 is provided, while a locking part 31 is pivotally attached at one end to the cam 15 for making the fashioning needles inoperative if no fashioning is desired.

As shown in Figures 1 and 13 the cam 30 presses the jack needle 13 by engaging its wing 25 into position to cover the cylinder needle and the loop holder slips out of the loop and thread drops onto the cylinder needle.

In Figure 1, a wire 36 is shown which serves the purpose of preventing the needle from closing when it is being pushed out for transferring. All needles are being pushed out to a position where their own thread open the throat but does not cast off, the needles which are to fashion are pushed out by the jack card so that they throw the stitch off, and the wire 36 prevents the throat from closing and holds it open

until the transfer jack falls on the needle. The attachment operates as follows:

During the rotation of the cams of the knitting needle bed in the direction of arrow 32, the cam arrangement 17, as shown in Figs. 5 to 12, will push the respective knitting needle 18 out of the bed, while the cam arrangement of the transfer jack needles will bring the jack needle into a position to approach the pushed out knitting needle, the throat of which has been opened by the thread or a wire as it is customary with such machines. The further operation of its cam arrangement 34 will lift the transfer jack into position above the dial or knitting needle as shown in Figure 6, and the thread 33 will assume a position indicated in Figure 6.

The further operation of its cam arrangement will let the throat of the jack needle fall upon the dial needle (Fig. 7).

Thereupon the knitting needle will move back and pull the jack needle with it into position indicated in Figure 8, so that now the thread 33 of the knitting needle is transferred to the jack needle as shown in Figure 9, and closes the latch while slipping off.

As shown in Figure 10, the jack needle is then moved forward by its own cam 15 in order to disengage from knitting needle and carries the thread along. Thereafter the jack needle is lifted by cam 35 lifting the thread out of the knitting needle whereafter the jack needle pulls the thread over the looper 26 which transfers the thread to the cylinder needle which at this moment starts to raise into position to approach the loop holder.

As the general arrangement of a needle bed, particularly in this case is so that in line with every horizontal needle is located a jack needle and the vertical knitting needles are arranged staggered in relation to the horizontal needles, it is necessary to twist the jack needle during the transfer operation at a slight angle to bring it in line with the vertical needle. This is accomplished by a cam 30 mounted so as to operate with the cam section of the jack needle beds. As soon as cam 30 is in alignment with the jack needle 25 it will move the jack needle 13 slightly towards the right direction and so bring the thread right upon the vertical needle.

The loop holder 26 which moves with cam 30 will thus bring the closed thread loop B into an open position C and allow the vertical needle to be pushed upward by its cam into the thread loop.

The further movement of the loop holder 26 clears the thread and loop after cam 30 clears projection 25 jack needle 13 snaps back into its original position. At that moment the cam 35 allows jack needle 13 to drop down to its horizontal position on the sloping part of its cam face and so frees the thread entirely to permit the vertical needle to pull it down and complete the stitch.

The operation of the attachment will be entirely clear from the above description of the parts without further explanation.

Each jack needle as shown in Figure 3 has a boss 23 for the engagement by the cams, a throat 24 upon which the thread is transferred in the manner above described and a laterally extending inclined wing 25 for engagement by the cam 30 swinging the jack needle in alignment with the knitting needles.

It will be understood that I have disclosed the preferred form of my fashioning attachment for

knitting machines as an example only of the many possible ways to practically construct the same, and that I may make such changes in the general arrangement thereof and in the construction of its minor details, as come within the scope of the appended claims without departure from the spirit of my invention and the principles involved.

Having thus described my invention, what I claim as new, and desire to secure by Letters Patent is:

1. A transfer attachment for knitting machines of the character described including their needle beds, comprising an additional needle bed for a plurality of fashioning jacks arranged to co-operate with the knitting needles of the machine, means to gradually transfer the thread from said knitting needles to said fashioning jacks, a loop holder for holding the thread during the transfer of the thread from said jacks to the vertical needles a cam to swing the jacks into proper position to the knitting needles for the transfer of the thread, and means pivotally attached to one of the cams controlling the transfer of the thread

from the knitting needles to the jacks and to lock the fashioning jacks if no transfer is desired.

2. A transfer attachment for knitting machines of the character described including their needle beds, comprising an additional needle bed for a plurality of fashioning jacks on said attachment arranged to co-operate with the selected number of knitting needles of the machine, cam arrangements in said attachment to gradually transfer the thread from said knitting needles to said fashioning jacks, a loop holder for holding the thread during the transferring of the thread from said jacks to the vertical needles, a cam to swing the jacks during the transfer of the thread into alignment with the knitting needles, a means for returning the fashioning jacks into their normal position after the transfer of the thread to the vertical needles to permit the completion of the stitch by said vertical needles, and a locking pawl pivotally attached to one of the cams controlling the operation of the jacks for holding the jack needles inoperative if no fashioning operation is desired.

MORRIS PHILIP.
